Primary Examiner — Jennifer Rivard(74) *Attorney, Agent, or Firm* — Renner, Otto, Boisselle & Sklar, LLP(57) **CLAIM**

I claim the ornamental design for a combined snuff box disposal lid and top lid, as shown and described.

DESCRIPTION

FIG. 1 is a top perspective view of a combined snuff box disposal lid and top lid showing my new design.

FIG. 2 is an end elevational view of the combined snuff box disposal lid and top lid, the opposite end elevational view being a mirror image thereof.

FIG. 3 is an opposite end elevational view of the combined snuff box disposal lid and top lid.

FIG. 4 is a top plan view of the combined snuff box disposal lid and top lid; and,

FIG. 5 is a side elevational view of the combined snuff box disposal lid and top lid, the opposite side elevational view being a mirror image thereof.

The broken lines in the figures depict environmental structure and do not form a part of the claimed design.

The bottom view is non-ornamental and does not form a part of the claimed design.
